DRAFT CONTROL

Oscar E. Wadenstein, St. Paul, Minn., assignor, by mesne assignments, to Fuel Reduction Engineers, Inc., St. Paul, Minn., a corporation of Minnesota.

Application June 3, 1949, Serial No. 97,018

8 Claims. (Cl. 236—15)

1 My invention relates to an improvement in the draft control provided by a by-pass type of damper, wherein it is desired to provide a simple and effective means to furnish varying rates of over-fire draft depending upon the requirements of boilers or furnaces, whether fired by coal, oil or gas.

During recent years it has become common practice to regulate a motorized by-pass type of damper in the breeching between the boilers and the stack. A static pressure regulator is provided to measure the static pressure above the fire bed and relays are controlled by this regulator for actuating the damper motor. With this system a substantially constant rate of over-fire draft may be maintained by more or less closing the by-pass damper in the breeching to increase over-fire draft or by opening the damper to a greater or lesser extent to decrease over-fire draft by bypassing stack suction. However, the common types of motorized by-pass dampers described above are limited to a single rate of over-fire draft dependent upon the setting of the static pressure regulator in use.

I have found that boilers or furnaces will operate more economically if over-fire draft is varied to supply more or less draft as the volume of fuel and air is increased or decreased. Thus in my variable air flow control I provide up to three static pressure regulators with each regulator adjusted to provide a different fixed rate of over-fire draft depending upon the requirements of the fire. Three static pressure regulators, each activated separately by electricity, will provide three rates of draft; for example .12" draft by water for a peak boiler load, .08" for a half load and .04" for a quarter load. Two static pressure regulators will provide two rates of over-fire draft. As control is switched from one static pressure regulator to the other by electricity, the over-fire draft will modulate or vary between the fixed settings of the regulators. Consequently, modulating draft is also a part of the present invention.

An added feature of the present invention lies in the provision of a means for controlling over-fire draft at lowest desirable rates of draft. I have demonstrated that the combustion efficiency of a fire, whether coal, oil, or gas, can be maintained at a high point of efficiency when over-fire draft is decreased as fuel and blower air ratios are decreased.

These and other objects and novel features of my invention will be more clearly and fully set forth in the following specification and claims.

2

In the drawings forming a part of my specification:

Figure 1 is a diagrammatic perspective view showing a furnace to which my control has been applied.

Figure 2 is a diagram of the wiring of my system.

The control system is used in conjunction with a furnace or boiler 10 which may burn any desired type of fuel. In the furnace illustrated an oil burner 11 is employed. The oil burner is provided with a blower 12 to supply primary forced air, and a dampered opening into the furnace below the oil burner to supply secondary air by stack suction. The furnace 10 is connected to the breeching 13 which connects the furnace with the chimney stack 14.

The oil burner 11 is supplied with oil from an oil supply line indicated at 15, which passes through a control valve 2. A lever 3 controls the valve 2 and also an electric control such as a multi-position switch or a rheostat 4. Pivotal movement of the lever 3 simultaneously increases or reduces the oil supply and the air supply provided by the blower 12. The rheostat 4 is connected to the blower 12 by an electric conduit 5.

The lever 4 is connected by a chain or other linking means 6 to the switch 35 which will be later described in detail. A means is provided for actuating the lever 4, such as the pressure actuated apparatus 7 connected to the lever 4 by a link 8. When the pressure actuated device 7 indicates a need for increased fuel and air feed the lever 4 is oscillated upwardly. When the necessary pressure is built up in the device 7, the lever is swung downwardly to decrease the fuel and air supply. The switch 35 is connected to the remainder of the system by a conduit 9. This system is only illustrative of many which could be used.

Obviously the oil burner is optional, and gas or coal can also be used. The gas may be supplied in the usual manner and a blower such as 12 may be used in conjunction therewith to supply a forced draft of air. Similarly the furnace or boiler 10 may comprise a coal-burning apparatus supplied with coal by a suitable stoker or similar device. A blower such as 12 is also used in conjunction with this type of furnace or boiler. The breeching 13 is provided with a by-pass passage 15 provided with a damper 16 at its outer extremity. The position of the damper 16 is controlled by means of a damper control motor 17. The motor 17 may operate in either direction to open or close the damper 16.

A static pipe 19 extends into the furnace above the grate level or into the breeching or boiler uptake. This static pipe 19 is connected to a first static pressure regulator 18, a second static pressure regulator 20, and a third static pressure regulator 21, if three over-fire draft settings are desired. The static pressure regulator 18 is set to maintain a relatively low static pressure differential to provide a low draft rate, while the regulator 20 is set to maintain a relatively high static pressure differential, to provide a high rate of draft. With the use of a third static pressure regulator 21 a medium rate of over-fire draft can be provided. Over-fire draft will modulate up or down as electric current activates the various static pressure regulators, one at a time.

With reference to Figure 2 of the drawings, it will be noted that two terminals 22 and 23 and the first static regulator 18 are connected by conductors 24 and 25 to terminals 26 and 27 of the damper motor 17. Terminals 29 and 30 of the second static pressure regulator 20 are provided with conductors 31 and 32 which are electrically connected to the conductors 24 and 25 respectively. A third terminal 33 of the first pressure regulator 18 is connected by a conductor 34 to one terminal of a triple throw switch 35. The third terminal 36 of the pressure regulator 20 is connected by a conductor 37 to the opposite pole of the triple throw switch 35. A third terminal 39 on the damper motor 17 is connected by a conductor 40 to a line wire 41 or a suitable source of current of the desired voltage. The terminals 42 and 43 of the triple throw switch 35 may be alternately connected to the other line wire 44, providing a suitable source of supply of electrical current.

Where a third static pressure regulator 21 is employed, the terminals 45 and 46 thereof are connected by conductors 47 and 49 to the conductors 31 and 32, and consequently the conductors 24 and 25, respectively. In other words, the three static pressure regulators 18, 20, and 21 are connected in parallel to the damper motor 17.

The third terminal 50 of the regulator 21 is connected by a conductor 51 to a third terminal 52 of the triple throw switch. The terminal 52, like the terminals 42 and 43, may be selectively connected to the line wire 44.

The damper motor 17 is of a reversible type. The conductor 40 which is connected to one line wire 41 is a common wire to the motor and forms one side of the circuit to the motor regardless of the direction of rotation thereof. The conductors 24 and 25 and the extended conductors 31 and 32, and 47, 49 connected thereto, respectively, form the remaining two sides of the circuits to the motor 17. When the conductor 24 and its extensions 31 and 47 are in circuit, the motor 17 will operate in one direction to open the damper. When the conductor 25 and its extensions 32 and 49 are in circuit the motor 17 will operate in the opposite direction to close the connected damper.

The switch 35 is controlled by some portion of the operating mechanism which is actuated simultaneously with any change of the fuel and air feed. The switch 35 acts to connect the line wire 44 to the conductor 34 through the switch terminal 42 when the boiler is being supplied with fuel and air at a minimum rate. Thus during the periods of relatively slow fuel feeding operation (as for example, one-quarter load), the static pressure regulator 18 is electrically connected in the circuit and variations in pressure above the fire bed will act to connect either the conductor 24

or the conductor 25 into the circuit and thus to move the damper motor 17 in one direction or the other. When the terminal 33 of the pressure regulator 18 is connected to the terminal 22, a circuit is closed through the conductor 24 so as to operate the damper motor 17 to open the connected damper 16. When the terminal 33 is connected to the third terminal 23, the circuit is closed from the conductor 34 to conductor 28, thus closing the circuit to the damper motor 17 to operate this motor in a direction to close the connected damper 16.

The pressure regulator is not specifically illustrated in detail in the drawings, as this device is known in the art. The regulator acts to maintain a fixed static pressure above the fire bed by opening or closing the by-pass damper to a greater or lesser extent. For example if the differential static pressure desired to be maintained by the regulator 18 is .04 inch of water, a switch contact will connect terminals 33 and 23 when the pressure decreases below this amount. As a result the damper 16 will be closed until the pressure above the fire bed again becomes .04 inch of water. When the static differential pressure above the fire bed increases above .04 inch, a contact will be formed between terminals 33 and 22, thus rotating the damper motor to partially open the damper 16 until the pressure above the fire bed again becomes .04 inch.

The static pressure regulator 20 acts in a similar manner when the furnace is feeding fuel at a maximum rate. When the fuel feeding apparatus is actuated to feed the furnace or boiler at full speed, the regulator 20 comes into action, and the damper setting of the damper 16 is controlled by this regulator 20. As a result, the draft will be maintained at a higher level during these feeding operations.

When the switch 35 shifts control of the damper motor from one pressure control to another, a gradual change in differential pressure is experienced within the furnace or boiler. For example, as the control shifts from the regulator 18 to the regulator 20, the static pressure differential must be increased due to the higher setting of the regulator 20. The by-pass damper 16 will therefore close to a greater extent until the static pressure called for by the regulator 20 is reached. Any increase of static pressure over the desired amount results in a closing of the circuit to open the damper 16 somewhat. Contact between the terminals 36 and 29 actuates the motor 17 to open the damper 16, while contact between terminals 36 and 30 actuates the motor 17 to close the damper 16.

Where a third pressure regulator 21 is employed to maintain an intermediate static pressure differential, as for example .08 inch of water, this regulator is cut into the circuit by the switch 35 when the fuel feed mechanism is feeding fuel at an intermediate rate; as for example, half speed. When the regulator 21 is in circuit, it acts in the manner described to maintain the desired static pressure differential.

If the pressure differential is excessive when the regulator 21 is placed in the circuit (as would be the case when the fuel and air feed to the furnace is reduced), the terminals 50 and 46 will be connected and a circuit will be formed through conductors 47, 31 and 24, opening the damper until the draft is reduced to the desired extent. Any reduction of draft below this will act to connect terminals 50 and 46, closing a circuit through conductors 49, 32 and 25 to close the damper.

Similarly, if the pressure differential is too little when the regulator 21 is placed in the circuit (as would be the case when the fuel and air feed to the furnace is increased from a lower speed) the regulator will tend to close the damper until the properly increased static pressure differential is reached.

The triple throw switch may be connected for control with the fuel feed mechanism in any desired manner. If the furnace or boiler is provided with controls to operate the fuel and air feed at three set speeds, the switch 35 may be controlled thereby to cut a corresponding regulator into controlling position. If the fuel feed fluctuates or modulates gradually from one feed range to another, the feed range may be divided into suitable smaller ranges, each of which may have its respective regulator.

I have found that my system operates with particular effectiveness in conjunction with a system including an air by-pass and by-pass damper in the breeching or stack. With this type of system the pressure above the fuel bed is controlled by allowing more or less air to enter the stack or breeching. As the by-pass damper opens, a greater amount of air enters the stack or breeching and the draft acting upon the fire bed is decreased. In other words, the suction effect upon the fire bed decreases and accordingly the pressure at this point increases, decreasing the static pressure differential. Conversely as the by-pass damper moves toward closed position less air is allowed to enter the by-pass so that a greater draft or suction effect is created to work upon the fire bed. As a result the pressure above the fuel bed decreases as the by-pass damper closes, and the static pressure differential increases.

This type of control functions more effectively than a control in which an internal damper is located in the breeching, stack, or boiler up-take. As such an internal damper moves toward closed position the air passing the damper merely tends to move at a higher velocity. Thus the damper does not greatly change the static pressure above the fuel bed until the damper nears closed position in many installations. Thus the maximum control is provided at a time when the internal damper is almost closed. Where the stack is high and there is substantial draft acting against a practically closed internal damper, boiler vibration or pulsation is severe. This fact combined with the fact that such a damper is subjected to high temperatures and may be injured thereby tends to cause my system to operate more effectively in conjunction with a by-pass system employing a by-pass damper.

It will be noted that during the peak operation of my furnace or boiler I maintain a fixed rate of draft over the grate level which has been found proper to produce good combustion. If the same rate of draft were maintained above the grate level during the low operation period of the boiler, poor combustion efficiency would result because of air due to excess draft. However, by decreasing the over-fire draft on low operation as fuel feed is decreased, greater combustion efficiency will result, because desirable fuel and air ratios are maintained and temperature loss is minimized.

In accordance with the patent statutes, I have described the principles of construction and operation of my draft control and while I have endeavored to set forth the best embodiment thereof, I desire to have it understood that ob-

vious changes may be made within the scope of the following claims without departing from the spirit of my invention.

I claim:

5. A damper control for use in conjunction with a furnace having a gas and smoke outlet, a by-pass into said outlet, a by-pass damper in said by-pass, and a fuel feeding mechanism which may operate at full or low speed intermittently, a first static pressure regulator for maintaining an above fire rate of draft of one relatively high value, a second static pressure regulator for maintaining an above fire rate of draft of a second relatively low value, a damper operating means, and means connecting each of said pressure regulators selectively to said damper operating means, and means controlled by the intermittent operation of said fuel feeding means for selecting the pressure regulator connected to said damper operating means, said controlled means selecting the first pressure regulator when said fuel feeding mechanism operates at full speed, and selecting a second pressure regulator when said fuel feeding mechanism operates at low speed.
10. The structure described in claim 1 in which the intermittent operation of said fuel feeding means electrically selects the pressure regulator connected to said damper operating means.
15. The structure described in claim 1 in which the pressure regulator operates upon an increase of draft to open said by-pass damper and operates upon a decrease in pressure above the fire to close the by-pass damper.
20. A variable air flow control for use in conjunction with a furnace provided with a stack through which gas and smoke may flow, a by-pass for by-passing air into the gas and smoke, a damper for regulating the by-pass of air through said by-pass, and a fuel feeding mechanism operable at various fuel feeding rates, the control including a static pressure regulating means, said regulating means including a plurality of elements each operable to maintain a predetermined static pressure differential above the grate level of the furnace, a damper motor connected to said damper for actuating the same, means connecting said elements with said damper motor for actuating said motor to maintain any of the predetermined static pressure differentials, and selecting means sensitive to variations in fuel feeding rates for selecting an element of said plurality of elements so as to maintain the desired pressure differential, said selecting means acting to select a greater pressure differential upon an increase in fuel feeding rate.
25. A variable air flow control for use in conjunction with a furnace provided with a stack, a connection between the stack and the furnace, a damper controlling the flow through said connection, and fuel feeding mechanism operable at a plurality of fuel feeding rates, the control including a first static pressure regulating means capable of maintaining a relatively high over-fire rate of draft, a second static pressure regulator capable of maintaining a relatively low above-fire rate of draft, each of said static pressure regulators being connected to the furnace and sensitive to changing conditions within the furnace, a member associated with said fuel feeding mechanism and sensitive to variations in fuel feeding rates, means for actuating the damper to open or close the same, means connecting each of said static pressure regulators to said damper actuating means to control the
30. The structure described in claim 1 in which the pressure regulator operates upon an increase of draft to open said by-pass damper and operates upon a decrease in pressure above the fire to close the by-pass damper.
35. The structure described in claim 1 in which the pressure regulator operates upon an increase of draft to open said by-pass damper and operates upon a decrease in pressure above the fire to close the by-pass damper.
40. A variable air flow control for use in conjunction with a furnace provided with a stack through which gas and smoke may flow, a by-pass for by-passing air into the gas and smoke, a damper for regulating the by-pass of air through said by-pass, and a fuel feeding mechanism operable at various fuel feeding rates, the control including a static pressure regulating means, said regulating means including a plurality of elements each operable to maintain a predetermined static pressure differential above the grate level of the furnace, a damper motor connected to said damper for actuating the same, means connecting said elements with said damper motor for actuating said motor to maintain any of the predetermined static pressure differentials, and selecting means sensitive to variations in fuel feeding rates for selecting an element of said plurality of elements so as to maintain the desired pressure differential, said selecting means acting to select a greater pressure differential upon an increase in fuel feeding rate.
45. A variable air flow control for use in conjunction with a furnace provided with a stack, a connection between the stack and the furnace, a damper controlling the flow through said connection, and fuel feeding mechanism operable at a plurality of fuel feeding rates, the control including a first static pressure regulating means capable of maintaining a relatively high over-fire rate of draft, a second static pressure regulator capable of maintaining a relatively low above-fire rate of draft, each of said static pressure regulators being connected to the furnace and sensitive to changing conditions within the furnace, a member associated with said fuel feeding mechanism and sensitive to variations in fuel feeding rates, means for actuating the damper to open or close the same, means connecting each of said static pressure regulators to said damper actuating means to control the
50. The structure described in claim 1 in which the pressure regulator operates upon an increase of draft to open said by-pass damper and operates upon a decrease in pressure above the fire to close the by-pass damper.
55. The structure described in claim 1 in which the pressure regulator operates upon an increase of draft to open said by-pass damper and operates upon a decrease in pressure above the fire to close the by-pass damper.
60. The structure described in claim 1 in which the pressure regulator operates upon an increase of draft to open said by-pass damper and operates upon a decrease in pressure above the fire to close the by-pass damper.
65. The structure described in claim 1 in which the pressure regulator operates upon an increase of draft to open said by-pass damper and operates upon a decrease in pressure above the fire to close the by-pass damper.
70. The structure described in claim 1 in which the pressure regulator operates upon an increase of draft to open said by-pass damper and operates upon a decrease in pressure above the fire to close the by-pass damper.

operation thereof, a selector in said connecting means for selectively connecting either of said static pressure regulators to said damper actuating means, and means connecting said member sensitive to variations in fuel feeding rate to said selector and operable to select said first pressure regulator when said fuel feeding mechanism operates at a relatively high speed, and selecting said second pressure regulator when said fuel feeding mechanism is operated at a relatively lower rate.

6. A damper control for use in conjunction with a furnace having a gas and smoke outlet, a by-pass into said outlet, a by-pass damper in said by-pass, and a fuel feeding mechanism which may operate at a relatively high speed or a relatively lower speed, said control including a first static pressure regulator capable of maintaining an above-fire rate of draft of a relatively high value, a second static pressure regulator capable of maintaining an above-fire rate of draft of a second relatively low value, a damper motor, a circuit to the damper motor including a switch actuated by variations in static pressure in said first static pressure regulator, a second circuit to said damper motor including switch means controlled by variations in static pressure in said second static pressure regulator, and means selectively connecting either of said circuits to said damper motor, and means actuated by variations in fuel feeding rate of said fuel feeding mechanism connected to said selector for actuating the same, said last named means actuating said selector for selecting the first pressure regulator when said fuel feeding mechanism operates at a relatively high speed and selecting said second pressure regulator when said fuel feeding mechanism operates at a relatively lower speed.

7. The structure described in claim 6 and including a third static pressure regulator capable of maintaining an above-fire rate of draft of an intermediate value, and a third circuit to said damper motor including switch means actuated by variations in static pressure in said third regulator, said selector being capable of selecting said

10

third circuit when said fuel feeding mechanism actuates at an intermediate rate.

8. A damper control for use in conjunction with a furnace having a gas and smoke outlet, a by-pass into said outlet, a by-pass damper in said by-pass, and a fuel feeding mechanism which may operate at two different rates of fuel feed, the control including a first static pressure regulator for maintaining a relatively high above-fire rate of draft, a second static pressure regulator capable of maintaining a relatively low over-fire rate of draft, a damper operating motor, a first circuit to said damper motor including a switch actuated by variations in static pressure in said first regulator, and said circuit also including a selector switch, a second circuit to said damper motor including a switch sensitive to variations in static pressure in said second regulator, and also including said selector switch, said selector switch being capable of connecting either of said circuits to a source of current, and means sensitive to variations in fuel feeding rate connected to said selector switch for actuating the same to select the circuit including said first pressure regulator when said fuel feeding mechanism operates at a relatively high rate and selecting said second pressure regulator when said fuel feeding mechanism operates at a relatively low rate.
